UNITED STATES PATENT OFFICE.

ARTHUR CLARE STRAYER, OF NEW BRIGHTON, PENNSYLVANIA.

FASTENER.

Application filed January 17, 1928. Serial No. 247,415.

This invention relates to fasteners and it is an object of the invention to provide a fastener of this kind adapted to be employed in connection with a box, and more especially a filing box to hold the cover effectively closed yet permitting ready and convenient removal of the fastener when it is desired to gain access within the box.

It is also an object of the invention to provide a fastener of this kind intended for use in connection with collapsible storage, file boxes and which obviates the use of strings, clips or the like for holding the box lid or cover in closed position.

15 The invention consists in the details of construction and in the combination and arrangement of the several parts of my improved fastener whereby certain important advantages are attained and the device rendered simpler, less expensive and otherwise more convenient and advantageous for use, as will be hereinafter more fully set forth.

The novel features of my invention will hereinafter be definitely claimed.

25 In order that my invention may be the better understood, I will now proceed to describe the same with reference to the accompanying drawing, wherein:—

Figure 1 is a view in perspective illustrating a fastener constructed in accordance with an embodiment of my invention and in applied position;

30 Figure 2 is a view similar to Figure 1 but showing the use of a plurality of fastener members;

35 Figure 3 is an enlarged sectional view taken through my improved fastener and the associated portion of the box to which it is to be applied, the coacting heads or buttons being shown in elevation.

40 As disclosed in the accompanying drawing, B denotes a box preferably of a collapsible file type including a conventional lid or cover member C which may be maintained in closed position by conventional snap fasteners, as indicated at 1. These snap fasteners 1 in themselves do not at all times possess the requisite efficiency to maintain the lid or cover member C closed as a result of the internal pressure which may be created by the contents of the box.

45 To assure a positive maintenance of the lid or cover member closed I provide the fastening member M. This member comprises an elongated flat strip 2 of metal provided at one extremity with an angular ex-

5 tension 3 preferably at right angles thereto, while the opposite end portion of the strip 2 is disposed outwardly, as at 4, to provide a finger especially designed to facilitate the removal of a fastening member M from applied or working position. In the present embodiment of my invention the extension 3 carries a resilient socket 5 which is adapted to be detachably engaged over an upstanding head or button 6 carried by the lid or cover member C with the extension 3 in close contact with the outer surface of said lid or cover member.

60 When the lid or cover member C is in closed position a head or button 6 is engaged through an opening 7 provided in the strip 2 with said strip 2 in close contact with the adjacent side wall of the box B. By this means the applied fastening member M 65 maintains the lid or cover member C effectively in closed position and in a manner to withstand the pressure exerted by the contents. However, the fastening member M may be readily and quickly removed when 70 desired or readily separated from the head or button 6 by exerting requisite pull upon the strip 2. This strip 2 possesses sufficient inherent resiliency to permit this operation 75 which is further facilitated by the outwardly curved portion 4.

80 In the embodiment of the invention is illustrated in Figure 1, I employ only a single fastening member whereas in Figure 2 I show the use of a fastening member M adjacent to each end of the box.

85 While I have herein disclosed the fastening member as being attached to the lid or cover member C through the instrumentality of interfitting socket and head, it is to be understood that the connection of the extension 3 with the lid or cover member may be effected in any desired manner, as for example, by fasteners embodying split shanks or any other medium or means which will 90 prove effective for the purposes desired.

95 It is also to be stated that by providing the strip 2 with a plurality of spaced openings 7 through which a head or button is selectively engaged, compensation may be 100 had for overcrowding of the box.

105 While I have hereinbefore specifically referred to my improved fastener being used in connection with a file box, it is also to be understood that it can be employed with boxes intended for other purposes.

110 From the foregoing description it is

thought to be obvious that a fastener constructed in accordance with my invention is particularly well adapted for use by reason of the convenience and facility with which it may be assembled and operated, and it will also be obvious that my invention is susceptible of some change and modification without departing from the principles and spirit thereof and for this reason I do not 10 wish to be understood as limiting myself to the precise arrangement and formation of the several parts herein shown in carrying out my invention in practice except as hereinafter claimed.

15 I claim:—

1. The combination with a box having a lid, of a pair of buttons, one secured in the lid and one secured in a side wall of the box, a fastening member comprising an elongated strip of resilient metal having a portion of one end turned to extend at right angles to the main body portion thereof, and a resilient socket carried by and opening through the angular extension of said fastening member, said extension being designed to overlie the top of the box to engage the button carried thereby in said socket, with the main body portion extending over that side of the box carrying a button, said body portion having an aperture therethrough to receive the button carried by the adjacent box wall.

2. The combination with a box having a lid, of a pair of buttons, one secured in the lid and one secured in a side wall of the box, a fastening member comprising an elongated strip of resilient metal having a portion of one end turned to extend at right angles to the main body portion thereof, and a resilient socket carried by and opening through the angular extension of said fastening member, said extension being designed to overlie the top of the box to engage the button carried thereby in said socket, with said main body portion extending over that side of the

box carrying a button, said body portion 45 having an aperture therethrough to receive the button carried by the adjacent box wall, said main body portion further having the free end thereof curved outwardly to stand away from the wall of the box, to facilitate 50 grasping of the body by the finger.

3. A fastener for a container having a lid and a side wall, comprising a strip of resilient material having a portion of one end extending at an angle to the main body 55 thereof, said angle portion being adapted to overlie the lid with the main body portion adapted to overlie the side wall, and studs carried on the lid and side wall, said strip being adapted to detachably receive the 60 studs.

4. A fastener for a container having a lid and a side wall, comprising a strip of resilient material having a portion of one end extending at an angle to the main body 65 thereof, said angle portion being adapted to overlie the lid with the main body portion adapted to overlie the side wall, studs carried on the lid and side wall, and a snap button carried by one of said portions for engagement with a stud, the other portion of 70 said strip being adapted to detachably receive the other stud.

5. A fastener for a container having a lid and a side wall, comprising a strip of resilient material having a portion of one end extending at an angle to the main body thereof, said angle portion being adapted to overlie the lid with the main body portion adapted to overlie the side wall, studs carried on the lid and side wall, and a snap button carried by one of said portions for engagement with a stud, said other portion of 75 said strip being adapted to adjustably engage the other stud.

In testimony whereof I hereunto affix my signature.

ARTHUR CLARE STRAYER.
